UNITED STATES PATENT OFFICE

2,028,377

TOY MENAGERIE CAGE

Adolphe Bernasconi, Rosebank, Richmond, N. Y.,
assignor to C. F. Mueller Company, Jersey City,
N. J., a corporation of New Jersey

Application August 3, 1933, Serial No. 683,428

5 Claims. (Cl. 46—11)

My invention relates to means for simulating enclosures or cages for animals, for example, for imitating the animal wagons employed in circuses, to furnish toys for the amusement and play of children, and the same has for its object to provide a simple and pleasing device which is formed at low cost from a blank of card board or similar material.

Another object of the invention is to provide a device of the character specified in which the enclosure thereof includes means for supporting tooth picks, matches, or similar pieces to form members simulating the usual bars for the front opening in animal cages.

Further, said invention has for its object to provide a device of the character specified in which the blank includes a partially cut out part simulating an animal and disposed in such relation to the enclosure as to be displayed, when bent or struck up from the plane of the blank, in the completed device within the confines of the enclosure.

Further, said invention has for its object to provide a device of the character specified in which the portion of the blank containing the animal simulating part serves in the completed device as a floor for the interior of the cage disposed substantially on a level with the bottom of the front opening to shield the bottom of the enclosure and improve the appearance of the device.

Further, said invention has for its object to provide a device of the character specified in which the pieces or members forming the bars for the cage are also retained in position by the bottom of the cage or enclosure.

Other objects will in part be obvious and in part be pointed out hereinafter.

To the attainment of the aforesaid objects and ends my invention consists in the novel features of construction, and in the combination, connection, and arrangement of parts hereinafter more fully described and then pointed out in the claims.

In the accompanying drawing—

Figure 1 is a view of one form of blank constructed according to and embodying my said invention;

Fig. 2 is a front elevation of the completed device made from said blank.

Fig. 3 is a transverse vertical section thereof on the line 3—3 of Fig. 2, and

Fig. 4 is a longitudinal section thereof on the line 4—4 of Fig. 3.

Referring to the drawing, at Fig. 1 is shown a blank 10 of card board or the like, of suitable

weight, from which the toy cage 10a is to be formed, as shown at Figs. 2 to 4. The blank comprises an intermediate bottom forming portion 11 between the transverse lines of bends 12 and 13, a back portion 14 between the transverse lines or bends 12 and 15, a top portion 16 between the transverse lines of bends 15 and 17, and a front portion 18 at one end of the blank having a juncture with the top portion 16 along the line of bend 17. The blank includes at the opposite end 10 an inner or false floor portion 19 connected to the bottom portion 11 by a relatively narrow securing portion 20 having a juncture with the bottom member 11 along the line of bend 13 and with the portion 19 along the line or bend 21. The material is preferably weakened or scored along the several lines of bend 12, 13, 15, 17 and 21 to facilitate bending.

The bottom portion 11 has semicircular cuts 22 therein terminating at the line of bend 12 to provide wheel simulating portions 23 adapted, when the bottom 11 and back 14 are bent about the line 12 into angular relation to each other, to project in the plane of the back 14 below the plane of the bottom 11 to form the lower half of wheels 25 at the rear of the enclosure, the simulation of the upper half of the wheels being preferably completed by printing or otherwise applying representations thereof on the back portion 14, as indicated at 24. The bottom 11 is preferably provided with a central hole 25 for a purpose hereinafter described.

The top and front portions 16 and 18 have end tabs or flaps 26 and 27 for closing the ends of the box-like enclosure to be formed by the portions 11, 14, 16 and 18, the tabs 27 being provided with end portions 28 adapted to be bent along the weakened lines of bend 29, and to be inserted into the body of the enclosure to retain the end covers in position.

The front portion 18 is formed with a relatively enlarged opening 30 for exposing the interior of the box-like enclosure to view when the enclosure is completed or formed and is also formed with the semicircular wheel simulating portions 31 in part projecting upwardly into the opening 30 and in part projecting below the free edge of said front portion 18, said portions 31 being also preferably printed or otherwise decorated to represent complete wheels at the front of the enclosure, as indicated at 32.

The floor portion 19 is provided with an intermediate animal or figure simulating part 33 formed by a line of cut 34 and adapted to be struck up or bent along the weakened line of 55

bend 35 out of the plane of said portion 19 into angular relation thereto. The portion 19 at the ends has tabs 36 adapted to be folded downwardly about the weakened lines of bend 37, and at 5 the rear thereof has a tongue 38 adapted to be received within a slot 39 at the lower part of the back portion 14 when the blank is formed into the box-like enclosure.

The front margins of the top portion 16 and 10 the false floor portion 19 are formed with series of holes 40 and 41 cooperating, when the device is completed, to receive tooth picks, matches or other stick-like members, which, if desired, may be made of edible substances such as fine 15 spaghetti, candy, etc., as indicated at 42 for forming the bars for the opening 35 at the front of the cage. The holes 40 in the false floor 19 serve to position the lower ends of the bars 42 and maintain the same properly spaced relative to 20 each other and against lateral movement while the bottom 11 serves to support the bars duly in vertical position.

To form the box-like enclosure 10^a, shown, the several portions 11, 14, 16 and 18 are bent into 25 angular relation to each other about the lines of bends 12, 15, and 17 to form the box, the narrow portion 20 being bent upwardly about the line of bend 13 to engage the inner surface of the bottom part of the front portion 18 as indicated at 43. The contacting portions 20 and 30 43 are secured together by a suitable adhesive or gum, applied by the manufacturer or later by the child, as desired, to either one of said portions 20 and 43. The false bottom 19 is then bent rearwardly about the line of bend 21 and the tongue 38 inserted in the slot 39, the downwardly deflected tabs 36 serving to support said floor 19 in spaced relation to the bottom 11.

The end flaps 26 are then bent downwardly 40 over the ends of the box and the flaps 27 bent rearwardly over said flaps 36 and the ends 28 inserted to close the box at the ends. By inserting a finger or instrument through hole 25, the partially cut out animal simulating part 33 can be struck up into a vertical position within the 45 cage 10^a.

When the box 10^a is completed the holes 40 and 41 are in aligned relation at the front of the cage for receiving the sticks 42 to form the bars 50 for the opening 30, the size of said openings being preferably such as to frictionally engage the sticks to firmly hold the same, and the bottom 11 serving also as means for preventing the sticks from dropping out.

The device embodying my invention is produced at low cost by a simple printing, cutting, and scoring operation to form a blank capable of being formed into the completed device. The flat blank as thus formed is particularly adapted 55 for use as a prize or advertisement in packages of food-stuffs of various kinds, the blanks occupying very little space in the packages.

The blanks may have printed thereon any desired advertising matter, and may be fabricated in quantity to simulate a number of different animals so that the collectors of such blanks can gradually acquire a toy menagerie containing a variety of caged animals.

Having thus described my said invention what 70 I claim and desire to secure by Letters Patent is:

1. A device of the character described comprising an enclosure including a top, side walls, bottom and a false bottom above said bottom, the front wall having an opening therein, and said top and said false bottom having holes therein contiguous to the opening in the front wall for receiving members forming bars engaging said bottom at the lower ends thereof to be supported in position thereby. 5

2. A device of the character described comprising 10 an enclosure including a top, side walls, one of said side walls having an opening therein, a series of bars for said opening, a bottom, and a false bottom above said bottom, said bottom serving to support said bars in vertical position, 15 said false bottom including means for securing the same in spaced relation to said bottom, means for maintaining the lower ends of said bars against lateral movement, and means for locking the false bottom to one of the side walls of said 20 enclosure; said false bottom having a cut therein to provide a part simulating a figure adapted to be struck up within the confines of the enclosure.

3. A device of the character described comprising 25 an enclosure simulating an animal cage and including a front portion having an opening therein, a top portion, a back portion, a bottom portion having a hole therein, and a floor portion within the enclosure in spaced relation to said bottom portion, and having a cut therein 30 forming a part adapted to simulate an animal and disposed to be struck up by applying pressure thereto through said hole, said top and floor portions having holes therein at the front, and bar forming members for said opening received in 35 said last named holes and adapted to be supported at the lower ends thereof by said bottom portion.

4. A device of the character described comprising 40 a blank having lines of bend therein providing portions for forming an enclosure, the front one of said portions having an opening therein, and other of said portions forming the top and bottom of said enclosure and a floor in spaced relation to said bottom, said top and floor portions 45 having holes therein contiguous to said opening for receiving members forming bars for said opening and engaging the bottom portion at the lower ends thereof to be retained in position thereby.

5. A device of the character described comprising 50 a blank having lines of bend therein providing portions adapted to form the front, top, back and bottom of an enclosure, said front portion having an opening therein for exposing the interior of the enclosure to view, a relatively narrow portion extending from said bottom adapted to be secured to the inner surface of said front portion below said opening to connect said bottom portion thereto and a portion at one end of the blank extending from said connecting portion 55 forming a false floor above said bottom portion, said false floor including means for retaining the same in spaced relation to said bottom portion and having a cut therein to form a part simulating a figure adapted to be struck up within the 60 enclosure, said top and said false floor being provided along their corresponding longitudinal edges with registering series of bar-receiving apertures located to the rear of the opening in, 65 said front. 70

ADOLPHE BERNASCONI.
